RIM ROLLING MACHINE

Filed March 19, 1927

INVENTOR:

Charles L. Wiles,

John P. Barber
ATTORNEY.

UNITED STATES PATENT OFFICE

CHARLES L. WILES, OF DETROIT, MICHIGAN, ASSIGNOR TO BUDD WHEEL COMPANY, OF PHILADELPHIA, PENNSYLVANIA, A CORPORATION OF PENNSYLVANIA

RIM ROLLING MACHINE

Application filed March 19, 1927. Serial No. 176,681.

The present invention has for its object the provision of a machine by means of which rings of irregular cross section may be formed expeditiously and economically.

5 The invention is described with reference to a ring of one specific cross section, namely, a tire retaining rim such as is used to mount pneumatic tires on wheels, but is broadly applicable to any similar shape which presents 10 a like problem of manufacture.

The preferred form of machine for carrying out the present invention consists primarily of coacting opposed rolling dies having faces as hereinafter described, but it is 15 to be understood that means other than rolling dies may be utilized to the same end, as for instance, opposed reciprocating dies having faces of cross sectional contour similar to the cross section of the coacting faces of the 20 rolling dies shown and described. If this is done, the reciprocating dies will, of course, be formed in a plurality of parts having arcuate radially movable rim engaging surfaces.

The accompanying drawings comprise— 25 Figure 1, a sectional view of a fragmentary portion of a machine embodying the invention,

Figure 2, an enlarged partial view in section, of the rolls taken in the plane of the 30 axes of the roll supporting shafts, and

Figures 3 to 6, similar views to a smaller scale illustrating successive steps in the formation of the rim.

In the formation of rings for commercial 35 use such as are represented in the present case by tire rims, it is often impossible to obtain raw material in the desired shape for bending into a ring or if possible, to bend such material into a ring successfully. It has 40 heretofore been the practice in cases such as the present one to manufacture rims of irregular cross section by bending stock of a somewhat similar section into a ring and then to give it its final form, or to perform 45 all the work of shaping the cross section after the ring has been completed by butt welding or similar joinder. In the case of the present rim section shown in Fig. 2, a peculiar difficulty exists in that the gutter G 50 of the rim is so formed that direct access to

its interior portions is practically impossible, thus rendering the usual rolling operations completely out of the question. In the past when it has been desired to form such a rim section, it has been done in two steps, 55 the stock for the ring being obtained in the form shown in Fig. 3. The first of these operations in the past has been to initiate by rolling a somewhat sharpened bend in the gutter G of the rim followed by another rolling operation which bends up the gutter bodily and causes it to assume an angular relation to the rest of the rim R, F as shown in Fig. 2. In the present case the same result is obtained in the one rolling operation by 60 means of rolls of the form shown in Fig. 2.

In the said Figure 2 rolls are shown, of a composite nature for convenience in manufacture and adjustment, by which the desired result is obtained. The upper roll U of the 70 pair comprises portions 8, 9 and 10 separated by suitable shims as at 15 to provide for the adjustments necessitated by roll wear and change of product. The lower roll L similarly comprises parts 18, 19, 20 and 21 separated by similar shims 25 for the same purpose. The first named roll U has surfaces 11 and 12 on the part 8 thereof, which consist of two cones, the one 11 being of a greater obtuseness than the other 12, merging into 75 the latter by means of an easy curve. On the part 9 of the upper roll U and adjacent the conical surface 12 is a substantially plane surface 13 which in combination with the conical surface 14 forms a sharp projecting annular 80 flange on the upper roll. The part 10 has a concave curved surface 17 and a cylindrical surface 16 adapted to form the balance of the rim by cooperating with a convex surface 27 and a cylindrical surface 26 on the corresponding portion 20 of the lower roll L. The other part 19 of the lower roll L consists of a cylindrical surface 24 which is an extension of the above mentioned surface 26 of the 85 part 20, a conical surface 22 which coacts with the surface 14 of the upper roll and a concave groove portion 23 which coacts with the edge of the annular flange 13, 14 of the upper roll in defining the exterior shape of the gutter. The conical portion 22 is pro- 90 95 100

vided with the proper dimensions to clear the portions 11 and 12 of the upper roll. In the closed position shown in Fig. 2, the upper and lower rolls define a closed pass of substantially the outline of the desired rim section. End portions 18, 21 of the lower roll are provided to render the insertion of a ring easier and more certain. Keys 6, 7 prevent rotation of the rolls U, L relative to the shafts S. These upper and lower rolls are mounted on the two shafts S of a rolling machine of the general nature shown in the patent to Grottes, No. 1,428,778 patented Sept. 12, 1922 for a "rolling machine." The said machine is adapted to rotate the two rolls continuously in opposite directions, to provide radial and lateral support for the rim which is engaged between the rolls, and to effect approach and separation movements of the two rolls to enable the loading of the machine with unrolled rings and the unloading of rolled rims therefrom. Heretofore, similar machines have been used for the same general purpose as that of the present invention but the production of the rim section chosen as illustrative has required that the work of formation be divided into two parts as outlined above. With the present roll structure only one operation is required.

The series of Figures 3 to 6 illustrate successive steps in the formations of the illustrated rim section by means of the improved apparatus. Figure 3 illustrates a ring of the rough stock positioned between the rolls which are at their widest point of separation. Upon the approach of the rolls to a position as shown in Fig. 4, the surface 11 of the upper roll engages the lip of the gutter g of the rim section being rolled and starts to force it to curl over. At the same time the rim base r is engaged by the surface 26 of the lower roll which begins to roll the base part of the rim to a true cylindrical shape. Upon further movement of the rolls together, as shown in Fig. 5, the entry of the projecting sharp cornered ridge defined by surfaces 13 and 14 of the upper roll into the gutter limits the curling over of the rim of the gutter, at the same time as the surface 14 bears on the portion of the rim between the rim base r and the gutter forcing it down and flattening out the angle therebetween. Similarly, the surfaces 17 and 26 of the upper and lower rolls, respectively, begin to give the final form to the ring flange f.

Figure 2 corresponds to the completion of the rolling operation in which the surfaces 16 and 17 of the upper roll and 24, 26, 27 of the lower roll have completed the formation of the rim base R and the flange F, the projecting sharp edged flange 13, 14 has pushed the bottom of the gutter G down into the groove 22 in the lower roll, the surface 13 has engaged the edge of the gutter G, limiting the curling tendency thereof, and the upper por-

tions of the surface 12 have formed the exterior edge of the rim of the gutter. Following this, the rolls will be separated as shown in Fig. 6 to permit the removal of the finished article and the insertion of another ring to be rolled.

Although the invention has been described in connection with a specific product, the scope thereof is not to be so limited but only as set forth in the following claims.

1. Apparatus for rolling wheel rims comprising co-operating rolls, having relative movements of approach and separation, one of said rolls having a surface corresponding substantially to the shape of the entire underside of the cross section of the finished rim, the other having surfaces of varying angularity which effect a shifting contact with said rim edge during approach of the rolls thereby bending the edge of said rim transversely to overhang the base of the rim.

2. An apparatus for rolling wheel rims comprising cooperating rotatable rolls having relative approach and separation movements, there being a substantially conical surface of varying angularity on one of said rolls which contacts with said rim at the edge thereof, and successively inwardly of said edge as the said approach movement occurs, whereby said edge is gradually curled up to overhang the base of the rim.

3. Apparatus for rolling wheel rims, comprising cooperating rolls, relatively movable in the axial plane common thereto, there being a substantially conical surface composed of zones of varying angularity on one of said rolls and an angular ridge adjacent thereto, a groove on the other of said rolls opposite said ridge, the said conical surface contacting initially with the edge of the rim on approach of the rolls and causing a bending thereof on further approach while the said ridge limits the amount of said bending and forms the rim to the shape of said groove.

4. An apparatus for rolling wheel rims comprising a pair of cooperating rolls, one of said rolls having a surface corresponding substantially to the entire underside of the cross section of the finished rim including the groove complementary to the underside of the gutter, and the other roll having a surface corresponding to the upper side of the cross section of the finished base and fixed flange of the rim, and a surface of substantially conical form adapted to engage the edge of the gutter supported in said groove and deflect the same transversely of the roll faces.

5. A machine for rolling rims comprising cooperating rolls having coating and complementary face portions corresponding to the cross section of a rim base, and the rim flange on one side thereof, a groove on one roll corresponding to the under side of the rim gut-

ter, a groove on the other roll corresponding to the edge of the finished product but lying inwardly of the plane of the outer edge of the first named groove, a ridge lying inwardly of the groove and having its inner side complementary to the inner side of the gutter and its outer side non-complementary to and spaced from the gutter, together with a leading-in surface for said groove of the gutter edge and of gradually increasing transverse inclination.

6. A machine of the character described, a pair of coacting rolls adapted to form the gutter of a wheel rim, one roll having a groove of the shape of the under side of the gutter, the other a coacting groove adapted to receive the edge of the formed gutter which groove lies inwardly of the outer edge of the first named groove, and a ridge adjoining the gutter edge groove and complementary to the inner side of the first named groove.

7. A machine of the character described comprising coacting rolls adapted to form in shape the gutter of a wheel rim embodying a groove in the face of one roll complementary to the underside of the finished gutter, a groove in the opposite roll complementary to the edge only of the finished gutter located in a plane inwardly removed from the outside of the first named groove and a leading-in surface for said second named groove.

8. In a machine of the character described, in combination, a pair of cooperating rolls, one of which is provided with a groove complementary to the under side of the gutter of a finished rim and the other of which is provided with a groove complementary to the edge of the finished rim gutter, together with a leading-in surface for said latter groove of gradually increasing inclination.

9. In a machine of the character described, a pair of cooperating rolls, one of which is provided with forming surfaces complementary to a rim base and lying substantially parallel to a roll axis, and also with a groove complementary to an inwardly inclined rim gutter and the other of which rolls is provided with complementary rim base forming faces and non-complementary gutter forming faces.

10. Apparatus for forming wheel rims comprising cooperating opposed dies, having relative radial approach and separation movements, there being a substantially conical surface of varying angularity on one of said opposed dies which contacts with said rim at the edge thereof and successively inward of said edge as the said approach movement occurs, whereby said edge is gradually curled to overhang the base of the rim.

11. Apparatus for forming wheel rims comprising cooperating dies, relatively movable in a common plane, there being a substantially conical surface composed of zones

of varying angularity on one of said dies, and an angular ridge adjacent thereto, a groove on the other of said dies opposite said ridge, the conical surface contacting initially with the edge of the rim on approach of the dies, causing a bending thereof on further approach, while the said ridge limits the amount of said bending and forms the rim to the shape of said groove.

12. An apparatus for forming wheel rims with a gutter comprising cooperating dies, one of said dies having a surface corresponding substantially to the entire underside of the cross section of the finished rim including the groove complementary to the underside of the gutter, and the other die having a surface corresponding to the upper side of the cross section of the finished base and fixed flange of the rim, and a surface of substantially conical form adapted to engage the edge of the gutter supported in said groove and deflect the same transversely of the die faces.

In testimony whereof he hereunto affixes his signature.
